(57) **CLAIM**

The ornamental design for an indication plate of snips, as shown and described.

DESCRIPTION

FIG. 1 is a perspective view of an indication plate of snips showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a perspective view of the indication plate of snips, illustrating the indication plate of snips applied on the snips. The broken line showing of the snips in FIG. 8 illustrates the environment of the claimed design and forms no part thereof.
